J. L. FOLSOM.

CARPET.

No. 17,808.

Patented Oct. 25, 1887.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 17,808, dated October 25, 1887.

Application filed September 21, 1887. Serial No. 250,638. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

The main feature of my design is a prominent stem-work, which is scroll-shaped in character. Along this stem-work is a succession of leaves, one end of each leaf partly encir-

cling the stem and the other end unfolding and 20 curving out into a scroll-shaped tip. These leaves are partly bell-shaped in outline. The broad end of one leaf frequently conceals the inner end of the adjoining leaf. Here and there upon or between the stem-work are large 25 circular flowers or groups of smaller circular flowers. At the ends of the scroll-shaped portions of the stem, also, there are irregular flower forms.

What I claim as new, and desire to secure by 30 Letters Patent, is—

The design for carpets, consisting of the design substantially as shown.

JAS. L. FOLSOM.
